UNITED STATES PATENT OFFICE

141,528

DESIGN FOR A CHILD'S JUMPER

James F. Ritter, Seattle, Wash.

Application February 21, 1945, Serial No. 118,068

Term of patent 14 years

(Cl. D34—5)

To all whom it may concern:

Be it known that James F. Ritter, a citizen of the United States, residing at Seattle, in the county of King and State of Washington, has invented a new, original, and ornamental Design for a Child's Jumper, of which the following is a specification, reference being had to the accompanying drawing, forming a part thereof, in which the figure is a perspective view of a child's jumper, showing my new design.

I claim:

The ornamental design for a child's jumper, as shown.

JAMES F. RITTER.
